(No Model.)

J. L. BOOTH.

HOISTING GEAR.

No. 295,725.

Patented Mar. 25, 1884.

UNITED STATES PATENT OFFICE.

JOHN L. BOOTH, OF HAMILTON, OHIO.

HOISTING-GEAR.

SPECIFICATION forming part of Letters Patent No. 295,725, dated March 25, 1884.

Application filed January 10, 1884. (No model.)

To all whom it may concern:

Be it known that I, JOHN L. BOOTH, (also commonly known as JOHN W. BOOTH,) a citizen of Great Britain, and a resident of Hamilton, Butler county, Ohio, have invented certain new and useful Improvements in Hoisting-Gear, of which the following is a specification.

This invention pertains to gearing for transmitting motion from the motor-shaft of a hoisting apparatus to the reel upon the same; and it relates particularly to the arrangement of a device for permitting a ready change in the speed and power of the transmission.

The invention will be fully understood from the following description, taken in connection with the accompanying drawings, in which—

Figure 1 is an end elevation of a hoisting-crab embodying my improvement; Fig. 2, a vertical section of the same, and Figs. 3, 4, 5, and 6 diagrams illustrating modifications.

In the drawings, A represents one of the housings of a hoisting-crab; B, the reel-shaft; C, one of the reel-flanges; D, the brake-lever, arranged to operate as usual; E, an internal gear formed upon the reel-flange; F, an external gear formed upon the reel-flange concentric with the internal gear, and provided with teeth of similar pitch; G, a pinion adapted to gear into either of the gears upon the reel-flange; H, the motor-shaft of said pinion, (shown in this case as being provided with a square for a hand-crank;) I, an oscillating lever, in which the shaft H is journaled; and J, a pivot for said lever, supported by the housing.

The lever I may be oscillated so as to bring the pinion G into mesh with either of the gears upon the reel-flange in a manner which will be clearly understood from the drawings, whereby motion may be transmitted to the reel at two different speeds, dependent upon which of the gears the pinion meshes with.

It is obvious that the device as thus far specified will require that the motor-shaft H have its motion reversed in order to maintain the proper direction of motion of the reel when the pinion is thrown from one gear to the other. For ordinary hand-crank hoisting ap-

paratus this may not be objectionable; but where objections to such reversal of motion exist the objections may be removed by the obvious use of an intermediate pinion, through which the pinion G may transmit its motion to one of the gears. Thus in Fig. 3 the pinion G may be thrown to engage directly into the internal gear, E; but in its other position it transmits its motion to the external gear, F, through the intervention of the idle-pinion K, by which means motion of the pinion G in one direction may be utilized to transmit motion to the reel at two different speeds always in the same direction.

In Fig. 4 the idle-pinion, instead of simply receiving the pinion G, is journaled to the lever so as to move with the pinion G, the effect being the same as with the device shown in Fig. 3.

In Fig. 5 the pinion G acts the same as in the device of Fig. 1; but the motor-shaft H, instead of driving that pinion directly, is located in the axis of oscillation of the lever, and drives that pinion through the instrumentality of the pinion upon the motor-shaft. The object of this modification is simply to suit cases where the rise and fall of the motor-shaft, in case it partakes of the motion of the pinion G, would be objectionable.

In Fig. 6 the center of the motor-shaft and the center of oscillation of the lever are so related to each other that the pivot I of the lever becomes an eccentric, as clearly shown.

I claim as my invention—

In a hoisting-gear, the combination of a reel-shaft, an internally-toothed gear, an externally-toothed gear of the same pitch, disposed concentric to said externally-toothed gear, a toothed pinion having a pitch corresponding with said gears, a lever supporting said pinion and fitted to oscillate upon a pivot having its axis coincident with the axis of said gears, and a motor-shaft adapted to impart motion to said pinion, substantially as and for the purpose set forth.

JOHN L. BOOTH.
